Fig. 1 is a front elevational view of a decanter showing my new design;

Fig. 2 is a front elevational view thereof, showing the stopper portion removed from the decanter;

Fig. 3 is a top plan view thereof;

Fig. 4 is a bottom plan view thereof; and

Fig. 5 is a fragmentary cross-sectional view thereof taken medially at the bottom.

In Figs. 1 and 2, the area between the horizontal lines above and below the restriction of the decanter is opaque and contrasts in appearance with the remaining transparent portions of the decanter.

I claim:

The ornamental design for a decanter, as shown and described.
